UNITED STATES PATENT OFFICE.

CHARLES L. PEIRCE, JR., OF PITTSBURGH, PENNSYLVANIA, ASSIGNOR OF ONE-HALF TO HUBBARD & CO., OF PITTSBURGH, PENNSYLVANIA, A CORPORATION OF PENNSYLVANIA.

INSULATOR-SUSPENSION BRACKET.

1,210,687.

Specification of Letters Patent. Patented Jan. 2, 1917.

Application filed May 17, 1916. Serial No. 98,033.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Insulator-Suspension Brackets, of which the following is a specification.

My invention relates to improved insulator supporting brackets adapted to be suspended from a messenger cable to support electrical circuits secured to the insulators.

Under some conditions it is impossible to set poles for the support of insulators for carrying transmission lines, as for example, across a body of water. Take for example the case of telephone lines, the spans are ordinarily one hundred feet long. Under some conditions a little heavier wire can be used to span greater distances but where the span is very long the wire, usually copper, would have to be of very heavy gage in order to be self-supporting and this would of course be expensive construction.

The object of my invention is therefore to provide brackets provided with clamping means adapting them to be clamped to messenger wires suspended across the long distance between two poles or towers, these brackets being in practice suspended the ordinary span distance apart and provided with insulators on which the transmission circuit of ordinary gage wire is strung. This is a cheaper, more efficient, and more satisfactory construction than where the gage of the transmission wires is increased sufficiently to make the wires self-supporting.

The bracket of my invention is constructed preferably of sheet metal dimensioned and formed to give maximum strength with minimum metal.

On the accompanying drawing the features of my invention are illustrated.

In these drawings Figure 1 is a side elevational view of a bracket clamped to a messenger wire, Fig. 2, is a rear elevational view thereof, Fig. 3 is a sectional view on plane 3-3, Fig. 1, and Fig. 4 shows the manner of forming the bracket from a length of T-bar.

The bracket structure comprises essentially a bracket member B and a clamp member C. The clamp member shown comprises the two jaw plates 5 and 6 through which extend the clamping bolts 7 and 8 to

securely draw the jaws together to clamp a messenger wire 9. Secured to the sides of the jaw plates and depending therefrom are the hanger links 10 and 11 between which the upper end of the bracket member B is secured as by means of a bolt 12 held in place by a cotter pin 13. Although any form of bracket member may be used the one shown has been found to be particularly efficient. As shown in Fig. 4, it is made from a length of T-bar whose web sections *a* and *b* are first cut away to leave the section *c*. The bar is then bent to substantially L-shape with its back 14 curved and its upper and lower ends 15 and 16 respectively vertical and horizontal. After bending of the bar to form the bracket the web section *c* forms a strengthening rib along the center of the back and this rib terminates short of the ends 15 and 16. The end 15 is held on the bolt 12 between the links 10 and 11 of the clamp, and the flat horizontal end 16 forms a seat for an insulator pin 17, the pin shown being of metal provided with the threaded shank 18 extending through the seat 16 and secured by nut 19, the upper end of the pin having a thimble 20 for receiving an insulator. The shape of the bracket structure is such that when it is suspended in service from the cable 9 it will hang to hold its pin vertical. The web *c* is widest at substantially the center of the back where the greatest strain occurs and gradually reduces in width to the ends 15 and 16, the strength being thus equally distributed without waste of material and without overweight.

In practice the cable 9 is strung between two poles and the brackets suspended therefrom at ordinary span distances apart and the line wire of ordinary gage is then secured to the insulators. The cable then takes up the entire strain and the transmission line is not subjected to any more strain than if it were strung in the ordinary manner on poles the ordinary distance apart.

I do not of course desire to be limited to the exact construction shown as modifications are no doubt possible which would still come within the scope of the invention.

I claim as follows:

1. A suspension bracket structure consisting of a one-piece bracket member comprising a horizontal part and a bend part and a diagonally extending vertical part, an insu-

2
lator receiving pin supported in vertical position on the horizontal part, a fitting secured to the upper end of the vertical part for hanging the structure from a support, 5 and a reinforcing web along the bend and vertical parts.

2. A suspension bracket comprising a clamp for engaging a suspension wire, an L-shaped bracket member of T-shaped cross- 10 section suspended from said clamp, and an insulator receiving pin supported on the horizontal limb of said bracket member.

3. An L-shaped bracket formed by bending a length of T-bar with its web extending 15 outwardly, an insulator receiving pin mounted on the horizontal limb of said bracket, and means secured to the ends of the vertical limb for suspending said bracket on a support.

20 4. An insulator supporting bracket formed by diagonally cutting away the web from a

length of T-bar and then bending such bar to L-shape, the remaining web section forming a strengthening rib at the bend of the formed bracket, an insulator receiving pin 25 mounted on the horizontal limb of said bracket, and means secured to the upper end of the bracket for securing it to a support.

5. An insulator supporting bracket formed by diagonally cutting away the web from a 30 length of T-bar and then bending such bar to L-shape, the remaining web section forming a strengthening rib at the bend of the formed bracket, an insulator receiving pin mounted on the horizontal limb of said 35 bracket, and a clamp secured to the upper end of said bracket for suspending the bracket member from a cable.

In witness whereof I hereunto subscribe my name this 11th day of May, A. D. 1916. 40

CHARLES L. PEIRCE, JR.
